DRAWING FRAME SLIVER CONTROLLING ENCLOSURE

Paul B. West, Kennebunk, Maine, assignor to Saco-Lowell Shops, Boston, Mass., a corporation of Maine

Application November 7, 1957, Serial No. 695,118

3 Claims. (Cl. 19—157)

This invention relates to drawing frame calendering mechanisms and more particularly to a novel sliver controlling enclosure for a web of sliver from the nip of the drafting element output rolls of a drawing frame to the nip of the rolls of the calendering mechanism thereof.

As is well understood by those skilled in this art, the sliver delivered by a drawing frame from the nip of the last pair of rolls thereof must be moved for a distance of several inches to the nip of a calendering mechanism which forms the input to the coiler portion or other take-up mechanism of the frame, such coiler portion disposing the sliver in the customary coiled formation in a roving can and so providing a take-up package. During such movement, however, the untwisted sliver tends to be opened up with the individual cotton fibers or the like being spread outwardly and released from the body of the sliver, principally because of the action of the conventional trumpet in squeezing air out of the sliver as the sliver enters it, but also because of the generation of static electricity and the effect of the sliver's movement through the air. In fact, in the case of modern high speed drawing frames, the speed of operation can readily be made great enough to cause the release of individual fibers from the body of the sliver in sufficient quantity so that the output end of such a frame resembles a miniature snowstorm, with considerable loss of fiber. As a result, the practical speed of operation of such frames is limited by the loss of fiber which can be tolerated rather than by the possible machine speed, and such operation is uneconomical. Furthermore, in addition to fiber loss, the sliver is invariably damaged to some extent, so that yarn and cloth subsequently manufactured therefrom is of inferior quality, and again, such damage increases as frame speed is increased.

Accordingly, it is an object of the present invention to provide a novel sliver supporting enclosure extending from adjacent the output rolls of a drawing frame to the trumpet adjacent the calender rolls thereof effective to permit the moving of a web of sliver from the nip of the output rolls of a drawing frame to the nip of the calendering mechanism thereof so that such sliver may be moved at the high speeds of which modern drawing frames are capable with greatly reduced and entirely tolerable fiber loss, tests with the apparatus of the invention having indicated that fiber loss is almost completely eliminated, and the quality of the sliver is much improved. In more detail, the invention is based on the principle of providing an enclosure whereby air squeezed out of the sliver by reason of the sliver's entry into the trumpet is returned in a direction countercurrent to the direction of movement of the sliver so that it can be absorbed into the sliver as the sliver is expanding upon passing from the nip of the drawing frame output rolls, the air stream being kept away from the sliver except in the region adjacent the output rolls to avoid large relative velocities between the sliver and the countercurrent air stream.

2

For the purpose of more fully explaining the various objects and features of the invention, reference is now made to the following description of a preferred embodiment of the invention, together with the accompanying drawings, wherein:

Fig. 1 is an elevation of a portion of a drawing frame with the sliver controlling enclosure of the invention thereon;

Fig. 2 is a plan of the sliver controlling enclosure 10 of Fig. 1;

Fig. 3 is a side cross section of the enclosure of Fig. 2 taken on the line 3—3 thereof; and

Figs. 4 and 5 are cross sections taken on the lines 4—4 and 5—5 of Fig. 3.

Referring to the drawings, the novel sliver controlling enclosure of the invention is in the shape of a generally flat bottomed horn with flaring sides pivotally mounted on the drawing frame roll stand D, said enclosure having its mouth opening adjacent the nip of the drawing frame output rolls R and its throat opening adjacent the calendering rolls C and in sealing contact with the face of trumpet T above such latter rolls. The trumpet T in effect forms a continuation of the horn throat so that sliver S is moved from output rolls R to calendering rolls C along the generally flat bottom of the enclosure, with the enclosure providing control of sliver movement as well as control of the air currents adjacent the sliver S.

Such air currents are affected as pointed out above, by the action of the output rolls R and trumpet T in compressing the sliver, since such compressing expels air from the sliver. Furthermore, the resiliency of the sliver causes reabsorption of air when freed from the nip of said rolls, so that air is being drawn into the sliver immediately following its release from output rolls R and is being expressed from the sliver by trumpet T immediately preceding calendering rolls C. Accordingly, a certain amount of air is continuously being conveyed from the trumpet T to the output rolls R and, with the enclosure of the invention, such air almost in its entirety will be continuously returned for absorption into the sliver. However, since such returning air must move countercurrent to the direction of motion of the sliver, it is important that air velocities at the surface of the sliver be controlled to a reasonably low value. This has been achieved in the enclosure of the present invention by providing an air passageway of sufficient cross-sectional dimension and spaced from the sliver S, such passageway taking the form of an upwardly extending enlargement or bulge in the otherwise flat upper surface of the horn 50 in the throat region of the horn so that the total cross-sectional area of the throat portion of the horn wherein countercurrent flow occurs is no less than about half that adjacent the mouth of the horn wherein absorption is occurring. Such unique horn shape accomplishes 55 return of the air expressed from the sliver without substantial disturbance of the sliver even at sliver speeds heretofore considered impractically high.

The preferred embodiment of the horn structure of the invention, as shown in detail in Figs. 2 through 5, 60 includes a generally flat sheet metal bottom or floor portion 10 and a top or cover portion 20. Said floor portion 10 has upwardly and inwardly turned flaring sides 12, the transversely extending mouth forming lower edge 14 at the forward end of said floor portion being pivotally mounted for upwardly swinging movement about transverse pivot shaft 16. Preferably, the floor portion near forward edge 14 is turned downward somewhat to facilitate entry of sliver. The rear edge 18 of said floor portion 10 normally rests on the flat upper face of trumpet T in a position to provide a smooth lead for sliver S entering said trumpet and to effectively seal the enclosure against the entry of air between such edge and

trumpet face. Due to the static electricity generating characteristics of moving sliver of cotton, wool or synthetic fiber, it is important that at least bottom portion 10 have an interior surface in contact with said sliver of non-static electricity generating material. The use of a conductive material, such as sheet metal having a good electrical connection to the drawing frame D, serves this purpose well, although plastic materials may also be used with appropriate surface treatment. The cover portion 20 is also generally flat with an upturned forward edge 22 to facilitate entry of the sliver S into the narrow rectangular mouth opening of the enclosure, and yet to prevent free air communication insofar as possible without interfering with such entry. A downturned rear edge 24 is also provided which edge extends beyond floor portion rear edge 18 around the remainder of the periphery of trumpet T and generally coinciding with its opening for smooth sliver lead. Preferably, a flange 26 is provided around the bottom of said edge 24 to aid in sealing. Flanges 28 are also provided along the flared sides of cover portion 20 to rest on and overlie the inwardly turned sides 12 of bottom portion 20 to provide an effective seal along the sides of the entire enclosure.

In accordance with the above recited principles of the invention, a bulge 30 is provided on the cover portion 20 in the region of the throat so that a passageway is provided for the returning air clear of the sliver surface. Such bulge begins in a smooth transition from the rounded rear edge 24 of the cover portion and extends upwardly and along the relatively narrow throat portion of the enclosure, it being of decreasing height beyond said narrow throat portion until it merges smoothly into the generally flat upper surface of the cover portion 20 about two thirds of the distance from trumpet T to the forward edge of the enclosure. As can be seen particularly clearly in Figs. 3, 4 and 5, the bulge 30 provides an aerodynamically clean passageway for the air expressed from the sliver at the trumpet T, in that such passageway merges smoothly both with trumpet T and into the relatively wide flat cover adjacent the mouth of the enclosure wherein air is continuously being absorbed into the sliver S. Furthermore, such bulge in the region of the relatively narrow throat portion of the enclosure provides an almost semi-circular cross-sectional configuration (Fig. 4) of much greater size than is needed for the movement of the sliver S alone so that an air passageway 32 of substantial area free of sliver can be provided so that air velocities adjacent the sliver surface are effectively reduced.

Due to the unusual shape of cover 20, as well as to the desirability of being able to observe the sliver, it is preferred that said cover 20 be of a clear plastic material, such as a vinyl, acrylic or styrene plastic, which can be readily formed as required, although metal could be used as well. With plastic, it is also preferable to treat the interior surfaces, so that they do not generate static electricity, although it is less important than it is with the bottom surface since sliver does not normally contact the surfaces of cover 20.

In operation, the sliver S passes from the nip of the drawing frame output rolls R along the floor of the horn-shaped enclosure of the invention and through the trumpet T as moved by calender rolls C. Since the enclosure of the invention fits closely to the trumpet T, the air squeezed out by the constriction of the trumpet is expelled into the throat region of the horn. Such air, as shown by the arrows in Figs. 2 and 3, then moves in a direction counter-current to the direction of movement of the sliver along the passageway formed by bulge 30 above the sliver, and is absorbed into the expanding fiber in the region of the mouth portion of the horn enclosure. This in effect provides a closed circuit for the air, and little can either escape or enter the enclosure, 75

so that not only is the sliver conveyed without damage, but any fly generated during its passage is largely reabsorbed by the sliver. The result is that little fly is produced around the output end of the drawing frame and any external dust, dirt, lint or fly is kept from the sliver, resulting in a cleaner drawing operation to provide superior yarn and cloth.

Various modifications of the invention within the spirit thereof and the scope of the appended claims will be apparent to those skilled in this art.

I claim:

1. In combination with a drawing frame having a pair of drafting element output rolls followed by a pair of calender rolls having an input trumpet for feeding drafted sliver to a take-up package, a sliver controlling enclosure for a web of sliver extending from adjacent the nip of said output rolls to adjacent said trumpet, said enclosure being in the shape of a horn having a narrow generally rectangular mouth opening of greater width than height positioned closely adjacent the nip of said output rolls and a throat opening positioned closely adjacent and above said trumpet, the bottom of said horn extending continuously from adjacent said output roll nip to said trumpet and the top of said horn being joined with said bottom to provide enclosed sides along the length of said horn, with the top of said horn in the region of said throat being bulged upwardly for a substantial distance but of decreasing height toward said mouth opening to provide a substantially flat top adjacent said mouth opening, whereby air expressed from said sliver by said trumpet moves along said bulge toward said mouth opening for reabsorption into the sliver as it expands beyond the nip of said output rolls.
2. In combination with a drawing frame having a pair of drafting element output rolls followed by a pair of calender rolls having an input trumpet for feeding drafted sliver to a take-up package, a sliver controlling enclosure for a web of sliver extending from adjacent the nip of said output rolls to adjacent said trumpet, said enclosure being in the shape of a generally flat bottomed horn with flaring sides and having a narrow generally rectangular mouth opening of greater width than height positioned closely adjacent the nip of said output rolls and a throat opening of generally semi-circular configuration positioned closely adjacent and above said trumpet in contact with the face of said trumpet, the generally flat bottom of said horn extending continuously from adjacent said output roll nip to said trumpet and having an interior surface of non-static electricity generating material, and the top of said horn being joined with said bottom to provide flared enclosed sides along the length of said horn, with the top of said horn in the region of said throat being bulged upwardly for a substantial distance but of decreasing height toward said mouth opening to provide a substantially flat top adjacent said mouth opening, whereby air expressed from said sliver by said trumpet moves along said bulge toward said mouth opening for reabsorption into the sliver as it expands beyond the nip of said output rolls.
3. In combination with a drawing frame having a pair of drafting element output rolls followed by a pair of calender rolls having an input trumpet for feeding drafted sliver to a take-up package, a sliver controlling enclosure for a web of sliver extending from adjacent the nip of said output rolls to adjacent said trumpet, said enclosure being in the shape of a horn having a sheet metal generally flat-bottomed floor portion with inturned flaring sides and a transparent plastic cover portion with inturned flaring sides and a transparent plastic cover portion having a flange resting on said inturned sides, said portions together providing said horn with a narrow generally rectangular mouth opening of greater width than height positioned closely adjacent the nip of said output rolls and a throat opening of generally semi-circular configuration positioned closely ad-

5 jacent and above said trumpet, the generally flat bottom of said floor portion of said horn extending continuously from adjacent said output rolls nip to said trumpet and resting on the face of said trumpet at a portion of the side of its periphery toward said output rolls, and the cover portion of said horn having its lower edge extending around the remainder of the periphery of said trumpet with the cover portion of said horn in the region of said throat being bulged upwardly for a substantial distance but of decreasing height toward said mouth 10

opening to provide a substantially flat top adjacent said mouth opening, whereby air expressed from said sliver by said trumpet rolls moves along said bulge toward said mouth opening for absorption into the sliver as it 5 expands beyond the nip of said output rolls.
